United States Patent Office

Des. 221,414
Patented Aug. 17, 1971

221,414

BED, STORAGE AND DESK UNIT

Mary Ellen Quirk, 163 Commonwealth Ave.,
Boston, Mass. 02116

Filed Apr. 22, 1970, Ser. No. 22,574

Term of patent 14 years

Int. Cl. D6—01

U.S. Cl. D5—4

H I S 1.

H I S 2.

FIG. 1.

FIG. 2.

FIG. 1 is a side view of a bed, storage, and desk unit showing my new design;

FIG. 2 is a front view;

FIG. 3 is a top plan view; and

FIG. 4 is a rear view thereof.

The side of the unit opposite that of FIG. 1 is a mirror image of FIG. 1. The desk platform of the unit and desk supporting legs are shown in slidably nested relation at the front end in FIG. 2.

I claim:

The ornamental design for bed, storage and desk unit, as shown and described.
